UNITED STATES PATENT OFFICE.

CARL HECTOR, OF ELIZABETH, NEW JERSEY.

SEESAW.

Application filed January 23, 1924. Serial No. 687,896.

To all whom it may concern:

Be it known that I, CARL HECTOR, a citizen of Germany, residing at Elizabeth, in the county of Union and State of New Jersey, have invented certain new and useful Improvements in Seesaws, of which the following is a specification.

This invention relates to improvements in amusement devices or playthings for children and particularly to types known as seesaws or teeter beams on which two persons may be exhilaratingly entertained.

One of the objects of the invention is to provide an unusually safe apparatus and which is far more comfortable to use than ordinary devices for the same purpose.

Another purpose is to produce a device that can be easily dismantled and moved, either indoors or out, as may be desired.

20 A further aim is in the provision of a device that is adjustable for height, rotatable in any preferred position, and in which the seats are individually adjustable along the beam so that the riders may 25 be balanced notwithstanding disparity in weight.

These objects, and others of a similar nature, are accomplished by the novel construction, combination and arrangement of 30 parts hereinafter described and shown in the accompanying drawing, forming a material part of this disclosure, and in which:—

Figure 1 is a perspective view showing 35 an embodiment of the invention as assembled ready for use.

Figure 2 is a partial side, partial sectional view of the same.

Referring more in detail to the drawing, 40 the numeral 10 designates in general, the base of the apparatus, the same being composed of two crossed strips of wood, having at their intersection a radial ball bearing 11.

A stationary circular plate 12 is supported by convergingly inclined supports 13, rigidly fastened at their lower ends to the cross pieces 10 near their outer ends.

50 Passing through a central opening in the plate 12 is a vertical post 14 having a reduced lower end 15 fitting the bearing 11, and fixed rigidly on the post is a collar 16 seated on the plate 12 to sustain the weight of the post and its attached parts.

The upper end 17 of the post is preferably 55 rectangular in cross section, as shown, and

contains a relatively narrow, elongated slot 18, the side walls of which have a plurality of transverse holes 19 to receive a pin 20.

Said pin may be engaged in any pair of holes and acts as a fulcrum for a lever-like beam 21 of suitable length and on its ends are mounted seats 22, having below them guide plates 23, between which elements the beam is slidably received and which may be used as foot supports.

60 A back 24 is supported at the rear of the seat by connections 25 rigidly fixed in the guide 23, and at the front are similar connections 26, leading to a narrow support 27 on which the hand rest 28 is rigidly mounted.

65 Passing through the beam 21, near its ends, are a plurality of holes 29 in which may be engaged pins 30, the same being provided with a head or eye to permit their ready extraction, said pins also passing through the seat and guide plates respectively 22 and 23.

70 The operation will now be considered; placing the stand, composed of the base and ring supported thereby, where it is desired, the post is entered and will freely turn therein.

75 The beam is passed through the slot in the post and secured by the fulcrum pin at such height as is deemed best and thereafter the seats are passed over the end of the beam and held in adjustment by the pin, locking the seats against sliding movement.

Obviously if one person is heavier than the other, the seats will be adjusted at different distances along the beam and the beam may be raised or rotated at any time in an easy manner.

80 From the foregoing it will be seen that an attractive, safe and interesting form of 85 children's diversion has been disclosed that fulfills its expressed objects.

Having thus described my invention, what I claim as new and desire to secure by Letters Patent, is:—

100 A see-saw comprising a rigid stand having upper and lower registering bearings, a rotatable post removably engaged therein and extending from the bottom, said post having an elongated slot in its upper extending portion and registering transverse holes in the walls of the slot, a lever beam, a fulcrum pin for said beam adjustably engageable in the mentioned holes, said beam having spaced roles in its end portions, 105 110

slides embracing the ends of said beam, one element of each slide acting as a seat and the other as a foot support, supports for the back of a rider associated with the seat, hand grips opposite said back supports and a pin passing transversely through said slide and edgewise of the beam whereby the

slide may be locked in adjustment, said pin having a head accessible to a rider above the seat.

In witness whereof I have affixed my signature.

CARL HECTOR.
